UNITED STATES PATENT OFFICE.

AXEL C. V. MALM, OF DAYTON, OHIO, ASSIGNOR TO THE EGRY REGISTER COMPANY, OF DAYTON, OHIO, A CORPORATION OF OHIO.

MANIFOLDING ATTACHMENT FOR TYPE-WRITING MACHINES.

1,144,146.

Specification of Letters Patent. Patented June 22, 1915.

Application filed November 28, 1914. Serial No. 873,480

To all whom it may concern:

Be it known that I, AXEL C. V. MALM, a citizen of the United States, residing at Dayton, in the county of Montgomery and State of Ohio, have invented certain new and useful Improvements in Manifolding Attachments for Type Writing Machines, of which the following is a specification, reference being had therein to the accompanying drawing.

This invention relates to manifolding attachments for typewriting machines and is in the nature of an improvement upon the attachment shown and described in Patent No. 1,130,751, granted to Malm, Rauh and Aker March 9th, 1915, and the application for patent filed by Malm and Rauh October 24th, 1914, Ser. No. 868,372. Manifolding attachments of the type shown in these applications comprise a supplemental ribbon-supporting frame mounted on the paper carriage of a typewriting machine, and a traveling paper support, adapted to support a plurality of rolls of paper, mounted in the rear of the machine to move along with and substantially parallel with the paper carriage. The paper support is connected with the paper carriage in such a manner as to cause it to move substantially in unison therewith. The paper support is mounted for very free movement so that it will impose little or no load upon the paper carriage and, consequently, there is a tendency for the paper support to rebound, and sometimes to cause the paper carriage to be moved rearwardly, when the forward movement of the paper support is suddenly stopped, as when the carriage is released and allowed to move to the full end of a line at one movement or when the tabulating attachment is being used.

The object of the present invention is to provide means to prevent the rebounding of the paper support under all conditions of work and to provide such means which will not interfere with the normal operation of the machine and the return of the paper carriage. To this end it is a further object of the invention to provide means for automatically releasing the paper support when the carriage return lever is actuated; and further to provide this means of such a character that the carriage may be returned independently of the carriage return lever.

In the accompanying drawings, Figure 1

is a plan view of a typewriting machine with the complete attachment applied thereto; Fig. 2 is a side elevation of the same, partly broken away; and Fig. 3 is a detail view of the detent and a portion of the rack.

In these drawings I have illustrated one embodiment of my invention and have shown the same in connection with a manifolding attachment, such as is shown and described in the above-mentioned applications. This attachment comprises a special ribbon supporting frame 1 mounted upon the paper carriage 2 of the typewriting machine 3 and supporting a supplemental ribbon 4 which is so arranged as to be carried across the printing point in a plurality of plies. Return movement is imparted to the paper carriage in the usual manner which, in the particular typewriter here shown, comprises a carriage return or line spacing lever 5. This lever is journaled on the carriage 2, connected by a link 6 with a pawl 7 adapted to engage a ratchet wheel 8 rigidly secured to the platen shaft 9, whereby the movement of the lever 5 will feed the paper forward one space and the continued pressure on the lever will return the carriage to its initial position, the carriage having been released from its holding devices by mechanism not here shown, but of the usual kind. In the particular construction here shown the pawl 7 is mounted on a stud 10 which is carried by the outer end of an arm 11 journaled on the platen shaft 9. Arranged in the rear of the typewriting machine is a base 12 having mounted thereon a track 13 which carries a supporting frame 14 for the paper supply, which, in the present instance, is in the form of rolls 15. The paper from these rolls is carried forward in superposed arrangement and interleaved between the plies of the supplemental ribbon 4. The paper supporting frame is connected with the paper carriage of the typewriting machine by means of an arm 16 which serves to cause the paper support to be advanced along with the paper carriage. The mechanism so far described is shown, described and claimed in the two applications for patents above mentioned and does not form a part of the present invention except so far as it enters into combination with the mechanism hereinafter to be described.

To prevent the rebounding of the paper support when its forward movement is sud-

denly checked I have provided a stop which is arranged adjacent to the track 13 and have mounted on the paper support a detent which coöperates with the stop to prevent 5 the return movement of the paper support. If the device is intended to operate to prevent the rebound of the paper support at the end of the track only, a single stop will answer but in the present instance the device 10 is designed for use with a tabulating device or other device in which the movement of the paper support may be checked at any point between the two extremes of its movement and I have, therefore, provided a 15 stop in the form of a rack or toothed bar 17 which is arranged parallel with the track 13 and, in the present instance, is in the form of a separate bar rigidly supported adjacent to one of the track members. It will be 20 obvious, however, that the rack may be formed in any suitable manner.

Coöperating with the rack is a detent or pawl 18 pivotally mounted on an axis extending transversely to the line of movement 25 of the paper support and adapted to travel over the teeth of the rack 17. Preferably, the teeth and the nose of the pawl are inclined sharply in the direction of travel of the carriage so that the pawl will ride 30 lightly over the teeth and the device will offer no appreciable resistance to the forward movement of the carriage. It will be apparent that this device will act to prevent return movement or rebounding of the paper 35 support at any point along the length of the track. Inasmuch as the teeth are short the detent will always be close to the vertical face of one of the teeth and, consequently, no appreciable movement will be imparted to 40 the paper support to cause the detent to engage its tooth. The detent is operable to enable the paper support to be released so that it may be caused to return to its initial position along with the paper carriage. To 45 this end an actuating device is connected with the detent and is arranged close to the front of the machine where it can be readily actuated by the operator. Further it is preferable that this actuating device be normally 50 connected with that part of the paper carriage by means of which its return movement is controlled so that the detent will be automatically operated to release the paper carriage when this controlling device is operated 55 to return the paper carriage to its initial position. As here shown the detent or pawl 18 is mounted on a shaft 19 journaled in bearings 20 mounted on the lower portion of the paper support and extending 60 transversely to its line of travel. A spring 21 is coiled about the shaft to hold the detent normally in engagement with the rack. Rigidly secured to the shaft 19 is a finger 22 arranged to be engaged by a second finger 65 23 which is mounted on an axis extending

parallel with the line of travel of the paper support and is so arranged that when it engages the finger 22 it will rock the shaft 19 in a direction to lift the pawl out of engagement with the rack and thereby release the paper support. The finger 23 is here shown as mounted on a shaft 24 extending lengthwise of the paper support and journaled at its ends in bearings arranged near the shaft 19 and the rear end of the paper supporting frame, respectively. To this shaft 24 is secured an arm 25, the free end of which is connected by a link or connecting rod 26 with a second arm 27 secured to a hollow shaft 28 journaled on a bearing stud 29 carried by the upper portion of the rear frame member of the paper support. A third arm 30 is secured to the shaft 28 and has pivotally connected thereto a rod 31 which extends forwardly to a point near the front of the typewriter where it may be actuated to impart rocking movement to the shaft 24 and thereby cause the detent to be moved into its inoperative position. Preferably means are provided for connecting the rod 31 with the carriage return lever 5. To this end the forward part of the rod 31 is provided with a slot 32 adapted to extend about the stud 10 on which is mounted the line spacing pawl 7 and to which stud movement is imparted upon each movement of the carriage return and line spacing lever 5. Consequently, each movement of this lever is imparted to the rod 21 and through the connecting devices to the pawl 18. It is sometimes desirable, however, to adjust the paper carriage independently of the carriage return lever and I have therefore provided the forward end of the rod 31 with a finger piece 33 so arranged that it can be readily engaged by the thumb or finger of the typist to lift the rod 31 out of engagement with the stud 10 and to impart operative movement to the rod, which movement will actuate the detent to release the paper support, thereby permitting the adjustment of the carriage. It will be further noted that the rod 31 is of a light and more or less resilient character and that its connections are such that it will spring or bend slightly to permit the paper carriage to be moved relatively to the paper support, this movement of the carriage being permitted by the resilient character of the driving connection 16 between the paper carriage and the paper support. Thus, the carriage can be spaced back one or two spaces, by the use of the back spacing lever or otherwise, without releasing the paper support, thus avoiding the necessity of actuating the detent whenever the back-spacing lever is operated.

The operation of the device will be readily understood from the foregoing description and it will be apparent that I have pro-

vided a very simple device for preventing the rebounding of the paper support; which can be readily actuated either by hand or automatically to release the paper support 5 when the paper carriage is to be returned but which will effectively prevent all return movement of the paper support except when the detent is positively actuated.

While I have shown and described one embodiment of the invention it will be understood that this has been chosen for the purpose of illustration only, and that I do not desire to be limited to the details of construction shown and described, for obvious 15 modifications will occur to a person skilled in the art.

Having thus fully described my invention, what I claim as new and desire to secure by Letters Patent is:—

20 1. The combination, with a typewriting machine having a paper carriage, a traveling paper support, and a connection between said paper carriage and said paper support to cause movement to be imparted to the latter, of means to prevent the return movement of said paper support, and a device connected with said means and with said paper carriage to release said paper support and to impart return movement to said paper support and to said paper carriage.

25 2. The combination, with a typewriting machine having a paper carriage, a traveling paper support, and a connection between said paper carriage and said paper support to cause movement to be imparted to the latter, of a device to prevent the return movement of said paper support, and means arranged adjacent to said carriage to manipulate said device to release said paper support.

30 3. The combination, with a typewriting machine having a paper carriage, a traveling paper support, and a connection between said paper carriage and said paper support to cause movement to be imparted to the latter, of a device to prevent the return movement of said paper support, and means to automatically actuate said device to permit said paper support to return with said carriage.

35 4. The combination, with a typewriting machine having a paper carriage, a traveling paper support, and a connection between said paper carriage and said paper support to cause the movement to be imparted to the latter, of a fixed stop, a detent carried by said paper support to engage said stop and prevent the return movement of said paper support, and an actuating device connected 40 with said detent and extending to a point near the front of said typewriting machine.

5. The combination, with a typewriting machine having a paper carriage, a track, a paper support mounted to move along said track, and a connection between said paper

support and said paper carriage to impart movement to the former, of a toothed rack extending lengthwise of said track, a pawl pivotally mounted on said paper support, a rod having one end supported by said paper support and operatively connected with said pawl and having its other end supported by said paper carriage.

6. The combination, with a typewriting machine having a paper carriage, a lever 75 connected with said carriage, a traveling paper support, and a connection between said paper carriage and said paper support to cause movement to be imparted to the latter, of a device to prevent the return movement of said paper support, and means controlled by said lever to actuate said device to release said paper support.

7. The combination, with a typewriting machine having a paper carriage, a lever 85 connected with said carriage, a traveling paper support, and a connection between said paper carriage and said paper support to cause movement to be imparted to the latter, of a toothed rack extending substantially parallel with the line of movement of said paper support, a detent carried by said paper support and co-operating with said rack to prevent the return movement of said paper support and operatively connected 95 with said pawl and having its other end connected with said lever.

8. The combination, with a typewriting machine having a paper carriage, a carriage return lever for said paper carriage, a traveling paper support, and a connection between said paper carriage and said paper support to cause movement to be imparted to the latter, of a device to prevent the return movement of said paper support, and a connection between said device and said carriage return lever to actuate the former to release said paper support.

9. The combination, with a typewriting machine having a paper carriage, a carriage 110 return lever for said paper carriage, a traveling paper support, and a connection between said paper carriage and said paper support to cause movement to be imparted to the latter, of a device to prevent the return movement of said paper support comprising a movable detent, a rod operatively connected with said detent and with said carriage return lever, whereby the movement of the latter will actuate said detent to release said paper support.

10. The combination, with a typewriting machine having a paper carriage, a carriage return lever for said paper carriage, a traveling paper support, and a connection between said paper carriage and said paper support to cause movement to be imparted to the latter, of a device to prevent return movement of said paper support comprising a movable detent, a rod operatively connect- 130

ed with said detent and detachably connected with said carriage return lever, whereby said rod may be actuated either by said lever or independently thereof to actuate said detent and release said paper support.

11. The combination, with a typewriting machine having a paper carriage, a carriage return lever for said paper carriage, a traveling paper support, and a connection between said paper carriage and said paper support to cause movement to be imparted to the latter, of a device to prevent the return movement of said paper support comprising a movable detent, a rod operatively connected with said detent and detachably connected with said carriage return lever, said rod having a finger piece to enable it to be detached from said lever and actuated independently thereof.

12. The combination, with a typewriting machine having a paper carriage, a carriage return lever for said paper carriage, a traveling paper support, and a connection between said paper carriage and said paper support to cause movement to be imparted to the latter, of a device to prevent the return movement of said paper support, an operable connection between said device and said carriage return lever to actuate said device to release said paper support, said connection being a yieldable one to permit of the limited movement of said paper support relatively to said carriage.

13. The combination, with a typewriting machine having a paper carriage, a lever carried by said paper carriage, a traveling paper support, and an operative connection

between said paper carriage and said paper support to cause movement to be imparted to the latter, of a device to prevent the return movement of said paper support, an actuating rod supported at one end by said paper support and operatively connected with said device, and connected at its other end with the lever on said carriage, said connecting rod being yieldable to permit said paper support to have a limited movement relatively to said carriage.

14. The combination, with a typewriting machine having a paper carriage, a platen mounted on said paper carriage, and a lever mounted on said paper carriage and operatively connected with said platen, said connection comprising a stud, a traveling paper support, and a connection between said paper carriage and said paper support to cause movement to be imparted to the latter, of a device to prevent the return movement of said paper support, said device comprising an operable detent, an actuating rod having one end supported by said paper support and operatively connected with said detent, said rod having near its other end a slot adapted to engage said stud to operatively connect said detent with said lever and also having a finger piece to enable said rod to be disconnected from said stud and manually actuated.

In testimony whereof, I affix my signature in presence of two witnesses.

AXEL C. V. MALM.
